W. F. L. BETH,
APPARATUS FOR CLEANING FILTERS.
APPLICATION FILED DEC. 1, 1911.

1,153,751.

Patented Sept. 14, 1915.

UNITED STATES PATENT OFFICE.

WILHELM FRIEDRICH LUDWIG BETH, OF LÜBECK, GERMANY.

APPARATUS FOR CLEANING FILTERS.

1,153,751.

Specification of Letters Patent. Patented Sept. 14, 1915.

Application filed December 1, 1911. Serial No. 663,313.

To all whom it may concern:

Be it known that I, WILHELM FRIEDRICH LUDWIG BETH, manufacturer, subject of the German Emperor, residing at Lübeck, 5 Germany, have invented certain new and useful Improvements in Apparatus for Cleaning Filters, of which the following is a specification.

My invention relates to improvements in 10 apparatus for cleaning filters by shaking the same, and the object of the improvements is to provide an apparatus in which the movable parts of the operating mechanism are not subjected to the shocks caused by the 15 shaking operation, which shocks cause a rapid wear of the said movable parts.

With this object in view my invention 20 consists in providing an apparatus for shaking the filters in which the shaking member is actuated from the operating gearing, through the intermediary of a force which is devoid of positive transmission connections with that member. This shaking member is preferably constituted by the reciprocating piston of a motor which is adapted to 25 be operated by a suitable fluid under pressure or under a vacuum, and which is controlled by a rotating driving gear and transmits its reciprocating movement directly to 30 the filters.

Filters for dust-laden air have been proposed, (see for example, applicant's prior German Patents, Nos. 52,812, 105,489, 164,001 and 169,361), in which the cleaning of the 35 filters is effected through the agency of vibrating tapping fingers and similar devices that periodically strike the levers bearing the filters, whereby the latter are vehemently shaken. These cleaning devices, especially when applied to large or heavy filters, are open to serious defects, in that the aforesaid tapping fingers and levers are subjected to considerable wear and tear, and the former set up in the belts, gearing, or other 40 driving mechanism recoils of comparatively great intensity which are manifestly injurious thereto and which are transmitted in the form of intense shocks to the adjacent parts of the building; also, such devices, 45 when in action, are extremely noisy. The objectionable features aforementioned are completely avoided by the improved construction hereinabove briefly described, the piston member of the fluid-actuated motor 50 comprehended in this construction having

no intermediate gear or other mechanical connections with the driving mechanism.

In order that my invention may more clearly be understood, a structural embodiment thereof is illustrated in the accompanying drawing which shows a vertical section of the filtering apparatus and the apparatus for shaking the filters.

Referring to the drawing, a suitable number of filters *z* of any known or preferred construction are suspended from a rod *y* within a filtering chamber *m*. At their lower ends the filters are secured to the bottom *m*¹ of the filtering chamber, and through apertures *m*² the filters open into a funnel *b* 70 through which the dust deposited on the inner surfaces of the filters can be removed. The said funnel is provided with an inlet stud *g*, through which the dust-laden air is admitted to the filters. At its top the filter 75 chamber *m* communicates with valve-controlled suction means, preferably consisting of a valve chamber *s*¹ which at one side is connected by a pipe *q* to an exhaust fan, (not shown), said chamber containing a 80 hinged flap valve *s*. At its opposite side the valve chamber has an opening *o* through which pure air, preferably under pressure, can be admitted to the filter chamber when shaking the filters. The aforementioned flap 85 valve *s* is adapted to be rocked into one of two positions indicated in full and dotted lines, whereby the filtering chamber is connected either to the passage *q* and to the exhaust fan, or to the inlet *o* for pure air 90 under pressure. As shown the rod *y* is connected to a reciprocating member such for example as the reciprocatory piston *i* of a motor whose casing or cylinder *l* is secured on the top of the filtering chamber. In the 95 present construction a solid connection is shown between the reciprocating piston and the filters *z*, but I wish it to be understood, that my invention is not limited to such construction. A suitable motive fluid, such as 100 compressed air, is admitted to the cylinder *l* through a conduit *n*, and the piston is reversed after each stroke by any known or preferred means. In the example shown a drag cylinder *k* is used for this purpose 105 which slides within the cylinder *l* and is taken along by the piston *k* during its stroke in either direction. The cylinders *l* and *k* are provided with inlet and outlet ports *l*¹, *k*¹ and *l*², *k*², and corresponding inlet and 110

outlet ports are adapted to be brought in register by the reciprocation of the cylinder *k*. Thereby the motive fluid supply and the exhaust port *l*² are alternately connected to or disconnected from the cylinder *l* and the piston *i*, so that reciprocating movement is imparted to the latter.

The supply of motive fluid to the motor is automatically controlled, and the said controlling means is operatively connected with the hinged valve *s* in such a way that the exhaust fan is shut off from the filtering chamber and thereby the supply of impure air thereto is stopped when shaking takes place. 10 In the example shown, the controlling means consists of a spring actuated piston valve *h* which is operatively connected with the hinged valve *s* by means of a rocking lever *f* and a connecting rod *f*¹. In the position of 15 the parts shown in full lines, the motive fluid supply to the motor is opened, and the valve *s* connects the filter chamber to the atmosphere or to a supply of pure air under pressure and closes it against the exhaust fan. Therefore the exhaust fan is cut out 20 of operation and the filters are being shaken by means of the piston *i*. If the valve *h* and the hinged valve *s* are shifted to the right and into the position shown in dotted lines, 25 the admission of the motive fluid to the motor is closed, thus cutting the latter out of operation and the exhaust fan is connected to the filter chamber. Therefore, the shaking of the filters is stopped, and impure air 30 flows again to the filter chamber.

In the preferred form, the operation of the valve *s* and the valve *h* is automatically controlled at suitable periods. As shown, the operating means consist of a slowly rotating cam *a* which once for each rotation 40 lifts a rod *f*², connected to the lever *f*, into position for engagement by a rather rapidly rotating cam *d*. The said cams are mounted on a suitable bracket *t*. The cam *d* is rotated by means of a pulley *d*¹ and a belt 45 trained thereon, and the cam *a* is rotated by means of a worm gear *a*², *a*¹. At its rear the rod *f*² is forked and each of its branches is formed with a nose *r* and *e* respectively. 50 When the rod *f*² is lifted by the cam *a* the lower nose *e* is in position for engagement by the cam *d*, so that the rod *f*¹, the valve *h* and the flap *s* are shifted into the position 55 shown in full lines in which shaking takes place. As the cam *a* gradually proceeds the rod *f*² drops downward, with its nose *e* out of engagement with the cam *d* and with its nose *r* into position for engagement therewith, so that the valve *h* and the flap *s* are 60 shifted to the right and the cylinder *l* is shut off from the pressure fluid supply.

Though in describing the invention reference has been made to a construction in which the rocking valve *s* is directly operated by the gear of the valve *h*, I wish it to

be understood, that my invention is not limited to the construction shown, and that other means may be provided to move the valve *s*, such for example as a special motor, an electromagnet, or the like.

70

I claim herein as my invention:

1. In filter cleaning apparatus of the character described, the combination with a filter supporting member, of a reciprocable motor having a free piston that is directly 75 connected to the filter supporting member and operative to alternately distend and relieve such distension of the filters, and automatic controlling means for causing reciprocation of said motor at predetermined intervals.

2. In filter cleaning apparatus of the character described, the combination with a filter supporting member, and means for alternately submitting the filter chamber to 85 the action of compressed air and a vacuum, of a fluid-actuated motor having a free piston that is connected to the filter supporting member and operative to raise and lower the same to alternately tension and relieve such tension on the filters, and a controller operative to automatically time the operations of said motor and said compressed air and vacuum controlling means.

3. In filter cleaning apparatus of the 95 character described, the combination with a filter supporting member, and valve means for alternately submitting the filter chamber to the action of compressed air and vacuum, of a fluid-actuated motor having a free piston that is connected to said filter supporting member, and automatic controlling means common to said motor and valve, means for causing the motor at timed intervals to distend the filters while the filter chamber is subjected to the action of compressed air and to cause the motor to relieve such distension of the filters while the filter chamber is subjected to vacuum action.

4. In filter cleaning apparatus of the 105 character described, the combination with a filter supporting member, and means for alternately subjecting the filter chamber to compressed air pressure and vacuum, of a reciprocable motor having a free piston that 110 is directly connected to said filter supporting member, and an automatic controller operative to cause reciprocation of the motor in one direction while the filter chamber is subjected to the action of compressed air and to cause reciprocation of the motor in a reverse direction when the filter chamber is subjected to the vacuum action.

5. In an apparatus of the character specified, the combination of a fluid-actuated element, means for supplying motive fluid thereto, and a controller for regulating the fluid supply comprising a valve, a rod connected with the valve and having a pair of opposed projections, and a rotary driv- 125

130

ing member arranged to engage said projections alternately to shift said rod endwise in opposite directions.

6. In an apparatus of the character specified, the combination of a fluid-actuated element, means for supplying motive fluid thereto, and a controller for regulating the fluid supply comprising a valve, a rod connected with the valve and having a forked 10 end the branches of which are formed with a pair of opposed projections, and a rotary driving member disposed between said branches and arranged to engage said projections alternately to shift said rod endwise 15 in opposite directions.

7. In an apparatus of the character specified, the combination of a fluid-actuated element, means for supplying motive fluid thereto, and a controller for regulating the 20 fluid supply comprising a valve, a rod connected with the valve and having a pair of opposed projections, a rotary driving member, and means for periodically rocking said

rod to bring said projections alternately into position for engagement by said driving 25 member.

8. In an apparatus of the character specified, the combination of a fluid-actuated element, means for supplying motive fluid thereto, and a controller for regulating the 30 fluid supply comprising a valve, a rod connected with the valve and having a pair of opposed projections, a rotary driving member, and a slowly-rotating cam operative upon said rod to rock the same periodically 35 and bring said projections alternately into position for engagement by said driving member.

In testimony whereof I have hereunto set my hand in presence of two subscribing witnesses. 40

WILHELM FRIEDRICH LUDWIG BETH.
